UNITED STATES PATENT OFFICE.

JOHANN G. PETERSON, OF JERSEY CITY, NEW JERSEY, ASSIGNOR TO MANHATTAN ELECTRICAL SUPPLY COMPANY, OF JERSEY CITY, NEW JERSEY, A CORPORATION OF NEW JERSEY.

BASE MEMBER FOR SEPARABLE ATTACHMENT-PLUGS.

1,130,626.

Specification of Letters Patent.

Patented Mar. 2, 1915.

Application filed May 7, 1914. Serial No. 836,896.

To all whom it may concern:

Be it known that I, JOHANN G. PETERSON, a citizen of the United States, residing at Jersey City, in the county of Hudson and State of New Jersey, have invented certain new and useful Improvements in Base Members for Separable Attachment-Plugs, of which the following is a specification.

This invention relates to base-members for separable attachment-plugs, among the objects of the invention being the provision of an article of this character which is simple in construction, the parts of which can be inexpensively made and easily assembled and which when in assembled relation are maintained in such condition in a substantial manner.

In the drawings accompanying and forming part of the present specification I have shown in detail one of the several convenient forms of embodiment of the invention, which to enable those skilled in the art to practice the same will be set forth in the following description. I do not restrict myself to this disclosure; I may depart therefrom in several respects within the scope of the invention defined by the claims following said description.

Referring to said drawings: Figure 1 is a vertical sectional view of a base-member of a separable attachment-plug, embodying my invention. Fig. 2 is a bottom plan view of said base-member. Fig. 3 is a top plan view of the same. Fig. 4 is a bottom plan view of the contact shell. Fig. 5 is a like view of the core. Fig. 6 is a plan view of a washer.

Like characters refer to like parts throughout the several figures.

The present device is of a nature susceptible to advantageous use in connection with or as part of any separable attachment-plug, an example of such an article being shown in Letters Patent No. 1,093,468 granted to me April 14, 1914 and to which reference may be had. In said Letters Patent there is a body and a cap. In the present instance I will term the body a "base member," as this is what I understand to be the usual term applied to such an element, the invention residing in the body or base member of the attachment plug. Said base member involves in its makeup a core as 2 which is usually of insulating material and

fiber or any of the substances ordinarily employed in this connection, may be utilized for the formation of said core. The lower end of the core 2 is of reduced diameter as at 3, the reduction in diameter forming a shoulder 4 to constitute a bearing for the inverted flange 5 of the contact shell 6. While this shell is shown as threaded, this may not in all cases be necessary, it being understood that the invention is not restricted to this and similar details. The reduced portion 3 constitutes in effect an extension from the body or main portion of the core 2 and as a matter of convenience it is shown as being of approximately frustoconical form. While the contact shell 6, which as will be understood is of metal, brass being usually provided for this purpose, preferably closely hugs the main or body portion of the insulating core member 2, I do not rely upon this to prevent relative rotation of the parts but provide more positive means to insure this result, there being in the present case a key connection between the two parts. For instance the shell may as shown have one or more projections constituting such keys to fit keyways in the core member 2. There are generally two of such keys shown, being denoted by 7 and 8 and as illustrated extending inward from and in the plane of the flange 5; they are also approximately diametrically opposite each other. I prefer that these keys and the keyways also be of different shapes, and such shapes may vary decidedly; as illustrated the key 7 is rounded while the key 8 is rectangular, the key 7 being adapted to fit the key-way 9, while the key 8 is adapted to fit the keyway 10, the two keyways being in the core member and being formed in part in the extension 3 and lower substantially flat face of the body of the core 2.

By making the two keyways of different shapes and the keys of practically similar form, the assemblage of the parts in a proper manner is facilitated, it being important that the parts for a reason that will hereinafter appear, should be assembled in a specific manner. Extending into the core member from the upper portion thereof are the chambers 11 and 12 of duplicate form in which are situated contact devices such as the spring fingers 13 and 14 held in

place by the screws 15 and 16 and serving the same office as set forth in my prior patent to which I have alluded, one of these fingers 13 being connected with the shell 6, 5 presenting a lateral contact, while the other is connected with an end contact which is shown as consisting of a disk 17 disposed centrally of the lower end of the core 2 and as provided with an inwardly extending 10 hollow stud 18 fitted in the central socket 19 in the bottom of the core member 2. From this central contact or disk 17 the L-shaped projection 20 extends, the screw 16 extending freely through one branch of the angular extension 20 which as will be understood 15 is situated in the keyway 10, the head of the screw 16 having an electrical contact with the extension 20 and therefore with the contact 17. The threaded portion of this screw 20 16 is tapped into an outward extension of the contact finger 14 so as to put the said finger 16 into electrical connection through the described intervening parts, with the end contact 17. This screw 16 extends 25 through an opening such as the perforation 21 in the key 8, the opening being of such size that the screw 16 will be insulated therefrom at this point, this result being obtained by making said opening 21 of larger diameter than that of the screw, by reason of 30 which the wall of said opening is insulated from said screw 16. Interposed between the extension 10 and the shell 6 and surrounding the shank of the screw 16 is a washer 22 of 35 fiber or other insulating material, shown as flat and which further insulates the screw 16 from the shell 6. The screw 15 electrically connects the contact-finger with the lateral contact or shell 6, said screw extending 40 through an opening 23 which also may consist of a perforation, in the key 7. While the screw 15 is in electrical connection with the shell 6, it does not directly engage the same, there being a metal washer 24 inter- 45 posed between the head of said screw 15 and the key 7.

What I claim is:

1. A base-member for separable attachment-plugs, comprising a one-piece insulating core having an extension, and a shoulder at the junction of the body portion and extension, a contact shell surrounding the body portion, provided with an inturned flange bearing against said shoulder, said flange having inward projections constituting keys, and the extension and the body portion having keyways to receive said keys, the latter having perforations, a contact device in the core, a screw for holding said contact device in place, electrically connected with said shell, one of the projections having a perforation to receive said screw, a second contact device in the core, a second screw for holding the second contact device in place, an end contact having an extension to which the second screw is connected, the other projection having a perforation of greater diameter than and through which the second screw passes, an insulating material between said second extension and the contact shell. 50 55 60 65 70

2. An insulating base member for separable attachment plugs, a shell surrounding said base member and having an inturned annular flange, the base member having an annular shoulder against which said flange bears, contacts in the base member, a screw for holding one of the contacts in place and for electrically connecting the same with said shell, a second screw for holding the shell in place, insulated from said shell and connected with the other contact, and a central end contact electrically connected with the second screw and provided with a projecting stud, the base member being socketed 75 80 85 to receive said stud.

In testimony whereof I affix my signature in presence of two witnesses.

JOHANN G. PETERSON.
